UNITED STATES PATENT OFFICE.

HILLORY P. INGRAM AND HARRY I. INGRAM, OF DE RIDDER, LOUISIANA.

OIL-BURNER.

1,076,828.

Specification of Letters Patent.

Patented Oct. 28, 1913.

Application filed February 16, 1912. Serial No. 677,950.

To all whom it may concern:

Be it known that we, HILLORY P. INGRAM and HARRY I. INGRAM, citizens of the United States, residing at De Ridder, in the parish 5 of Beauregard, State of Louisiana, have invented a new and useful Oil-Burner.

This invention relates to an improvement in oil burners.

The primary object of the present invention is to provide means for thoroughly heating the oil and generating gas before the same is supplied to the burner.

With the foregoing and other objects in view which will appear as the description 10 proceeds, the invention resides in the combination and arrangement of parts and in the details of construction hereinafter described and claimed, it being understood that changes in the precise embodiment of 15 the invention herein disclosed can be made within the scope of what is claimed without departing from the spirit of the invention.

In the drawings—Figure 1 is an elevation of the complete apparatus, the burner 25 and oil heater being partly in section. Fig. 2 is a section on the line 2—2 of Fig. 1.

In the drawings, 10 designates the tank or oil receptacle which is partially filled with oil. Air is forced in said tank by 30 means of the pump 11 to create sufficient pressure to feed the oil to the burner. The pump is connected to the tank by the pipe 12, the tank being provided with a valve 14 which is set to maintain a predetermined 35 air pressure within the tank. The supply pipe 15 is connected to the tank at a point adjacent to its base, a valve 16 being positioned between the tank and the burner.

An auxiliary pipe 18 leads from the upper 40 portion of the tank 10 to the intermediate portion of the horizontally disposed pipe 15, there being a valve 18 interposed in the pipe 17. The pipe 15 communicates with a vertically disposed pipe 19, the pipe 19 com- 45 municating with a needle valve 20 which, in turn, communicates with a horizontally disposed tube 21. This tube 21 is arranged concentrically within the cylinder 22, the oil passing to the tube 21 and out through the 50 open end of said tube into the cylinder 22. The connection at 24 is disposed centrally

of the casing 22 with the vertically disposed pipe 25 supporting the burner 26 which is disposed above a pan 27, so the heated oil gasifying passes through the pipe 25 to the 55 burner 26.

The many advantages in a device of this character will be clearly apparent as it will be noted that the oil supply may be positioned at a point remote from the burner, 60 and the oil supplied to the burner, the oil being heated and gasified before the same passes to said burner. Attention is also called to the fact that the entire construction is such as may be easily and economically manufactured, the various parts being readily assembled.

Assuming that the valve 18 is open and that there is no air pressure in the tank 10, the liquid will stand at the same level in the 70 tank 10 and pipe 17. Upon closing the valve 18 and pumping air into the tank 10, the pressure will cause the liquid in the pipe 17 to rise to a higher level than in the tank, compressing the air between it and the valve 75 18. But the air pressure in the portion of the pipe 17 to the right of the valve 18 is always less than that on the other side of the valve, as the air in the tank 10 must sustain a column of liquid in the pipe 17 of 80 greater height than that in the tank 10. Thus, upon opening the valve 18, the temporary surging back and forth of the liquid in the tank 10 and pipe 17 in the attempt to reach equilibrium will cause sufficient de- 85 crease in pressure at the valve 20 to allow back pressure from the cylinder 22 to dislodge an obstruction in the valve 20. To put the device again in condition to operate as described, it will be necessary to release 90 the air under pressure close the valve 18, and again supply air under pressure to the tank 10, thereby again securing columns of liquid of unequal height in the tank and pipe 17.

What is claimed is:

In a device of the class described, a fluid-containing tank; a main pipe entering the tank adjacent the bottom of the tank; an auxiliary pipe forming a communication 100 between the main pipe and the upper portion of the tank; an air pump discharging

into the tank; a cut off valve in the auxiliary pipe and located adjacent the tank, the said valve being under the control of an operator; a casing; a burner below and communicating with the casing; and a valve interposed between the casing and the main pipe.

In testimony that we claim the foregoing

as our own, we have hereto affixed our signatures in the presence of two witnesses. 10

MILLORY P. INGRAM.
HARRY T. INGRAM.
